UNITED STATES PATENT OFFICE.

HARRY M. BROWN, OF BROOKLYN, NEW YORK, ASSIGNOR TO RICHARD ALBERT CANFIELD, OF PROVIDENCE, RHODE ISLAND.

SEAL-APPLYING MACHINE.

1,053,122.

Specification of Letters Patent. Patented Feb. 11, 1913.

Application filed July 11, 1912. Serial No. 708,866.

To all whom it may concern:

Be it known that I, HARRY M. BROWN, a citizen of the United States, residing at Brooklyn, in the county of Kings and State of New York, have invented a new and useful Improvement in Seal-Applying Machines, of which the following is a specification.

This invention relates particularly to machines for applying seals or stoppers to bottles; and the invention constitutes an improvement on the invention set forth in my United States application No. 650,295, filed September 19, 1911.

15 The primary object of this invention is to provide an improved, simplified, and cheapened construction for seal-applying machines, which possesses certain advantages in operation, as well as the indicated 20 advantages of manufacture.

25 A further object is to provide a machine of the character indicated which shall be of compact structure and capable of being operated easily and effectively by foot-power, the machine being automatic and 30 certain in the operation of selecting, delivering, and applying the seals, and the work devolving upon the operator being merely that of positioning the bottles and depressing the foot-treadle.

35 Further objects of the invention will appear from the description hereinafter given.

The invention is illustrated in its preferred embodiment in the accompanying drawings, in which—

Figure 1 represents a broken elevational view of the upper portion of a machine constructed in accordance with my invention; Fig. 2, a broken vertical sectional view 40 showing the lower portion of the machine, this view being supplemental to Fig. 1; Fig. 3, an enlarged broken vertical sectional view showing the inclined seal-applying tool and attendant parts; Fig. 4, a broken sectional view taken as indicated at line 4 of Fig. 3 and showing the neck-clamping means employed; Fig. 5, a view similar to Fig. 4, but showing the main jaws or levers 8 in section and the auxiliary jaws 8^a in open position. 45 Fig. 6, a section taken as indicated at line 6 of Fig. 4. Fig. 7 a broken elevational view of the seal or stopper-chute and associated escapement device. Fig. 8, a sectional view taken as indicated at line 8 of Fig. 7. 55 Fig. 9, an enlarged broken sectional view

taken as indicated at line 9 of Fig. 3 and illustrating the insertion of a seal or stopper; and Fig. 10, a broken sectional view taken as indicated at line 10 of Fig. 1.

In the preferred construction, as illustrated, A represents a tubular standard equipped near its upper portion with an inclined guide A'; B, a reciprocable stopper-applying or seal-applying tool mounted in the guide A'; C, a bottle-supporting device equipped with neck-clamping means C'; D, a treadle-actuated connecting rod extending through the standard A; E, a bent lever which is pivotally supported at its rear end, pivotally connected at its elbow with the upper end of the rod D, and in engagement at its front end with the plunger or seal-applying tool B; and F, a rotary seal-selecting and delivering device which serves to deliver seals through a chute F' to the path of the seal-applying tool, said device being actuated through the medium of connections F² connected with the plunger B. The rod or plunger D is held normally elevated by a coil spring 1 contained in the standard A. The lower end of the rod D is connected by a pivot 2 to a foot treadle 3 whose rear end is joined by a pivot 4 to a lug in the base of the standard A. The inclined guide A' is preferably cast integrally with the separately formed upper portion A² of the standard A; and there is also preferably cast integrally with the member A² a forwardly projecting arm A³ on which the bottle-support C is mounted. On the guide A' is mounted a bracket A⁴ which carries the stopper-selecting and delivering device F.

The plunger B is provided centrally with a slot 5 which receives the front end of the lever E, which is suitably rounded to work in said slot and to actuate the plunger B in both directions.

The novel bottle-supporting device C, which possesses important advantages, comprises an inclined bracket 6 which is secured to the inclined front end of the arm A³. On the upper side of the member 6 are supported a pair of main jaws, or levers, 8, which are attached by pivots 9. Each main jaw 8 carries an auxiliary neck-clamping jaw 8^a which is connected with the main jaw by a pivot 9^a. The main jaws 8 as also the member 6 are recessed to accommodate the bottle-neck. Each auxiliary jaw 8^a comprises a neck-engaging segment 10 and a

shank 10^a, the shank being housed in a slot in the main jaw. Each segment 10 carries a stud 11 to which is attached one end of a coil spring 11^a, whose opposite end is attached to a stud 11^b carried by the main jaw 8. The auxiliary jaws may be opened (see Fig. 5) to admit a bottle-neck 12, and will be held open by the springs 11^a which at this time will be out of line with the pivots 9^a. When the bottle-neck is inserted, the auxiliary jaws are thereby swung to the closed position (Fig. 4) and the springs 11^a tend to hold them thus. The opening movement of the auxiliary jaws is limited by the shoulders 10^b which engage the rear walls of the slots. The concave portions of the segments 10 are provided with brass inserts 10^c, which are suitably recessed or countersunk to engage and hold the external flange of the bottle-neck. The main jaws 8 are normally held in the open position by a spring 13 which connects their shanks, as shown in Fig. 4. The shanks of the jaws 8 are provided with beveled surfaces 14 adapted to be engaged by the tapered lower end 15 of a jaw-locking plunger 16 mounted in a tubular plunger 17 whose upper or rear end is equipped with a roller 18 which engages the elbow portion of the lever E. The plunger 16 is held yieldably projected with relation to the member 17 by a spring 19. It will be noted that when the rod D is drawn downwardly to cause the tool B to perform the stoppering operation, the plunger 16 will be forced between the shank portions of the main jaws 8, thereby causing a slight movement of said jaws which is sufficient to cause the auxiliary jaws 8^a to securely clamp the neck of the bottle. Thus, while the auxiliary jaws will open wide to admit the bottle-neck by a lateral movement and will swing to a closed position during the insertion of the bottle, the final clamping action is secured by the slight automatic closing action of the main jaws which is effected by the plunger 16.

The rear end of the lever E is mounted on a pivot 20 with which the frame member A² is equipped in the rear of the upper end 50 of the rod D. This is shown in detail in Fig. 10, where the pivot 20 is shown secured to the frame member by a set-screw 21. One end of the pivot 20 is equipped with a head 22 provided with a vertical perforation 23 which affords a guide for the lower end of a plunger 24 which forms a part of the device F² for rotating the stopper-selecting device F.

The stopper-selecting device F need not be described in detail in the present application. It will suffice to explain that it comprises a frusto-conical rotary hopper 26 which is secured to rotate with a shaft 27 equipped with a ratchet wheel 28 and actuated by a pawl 29 carried by a collar 30

which is oscillated by the plunger 24. When the plunger 24 is depressed, the pawl 29 serves to actuate the shaft 27 through the medium of the ratchet wheel 28; and when the plunger 24 rises, the pawl 29 rides idly over the ratchet teeth to gain a fresh hold on the ratchet-teeth. The hollow member 26 is fixed to and rotates with the shaft 27 and with the shaft also rotates a disk 31 which virtually closes the enlarged end of the rotary hopper 26 and is equipped at its inner vertical face with a series of permanent magnets (not shown), which serve to deliver those seals which are properly presented to the upper end 32 of the seal-chute F'. No claim is made in the present application to the details of construction of the stopper-selecting device F. It may be added, however, that stoppers are delivered in mass to the rotary hopper 26 through a charging chute 33. The operation of the device is to take the stoppers or seals from the interior of the rotary member 26 and deliver them, properly arranged, to the chute F', which is thus kept filled with seals.

The seals descend by gravity to the escapement device G, which will be understood by reference to Figs. 3, 7 and 8. The escapement device G comprises a pair of escapement members or pawls 34 located in recesses 35 with which the lateral or edge walls of the chute F' is provided, the members 34 being supported on pivots 36. Each member 34 has a lower stopper-engaging tooth 37 and an upper stopper-engaging tooth 38. The members 34 are also provided with actuating arms 39 adapted to be elevated by fingers 40 carried by a rock-shaft 41 which is equipped with an actuating arm 42. The actuating arm 42 is joined by a link 43 to the lower end of a slide 44 which is adapted to be moved downwardly by a yielding finger or spring 45 which is secured to the upper end of the plunger B. The small coil spring 46 connects the arm 42 to a frame-supported stud 47, so that the fingers 40 are held normally in elevated position shown in Fig. 3, corresponding with the position shown in Fig. 5. When the plunger B descends, it depresses the slide 44, thereby lowering the fingers 40 and permitting the arms 39 of the escapement pawls 34 to drop, thus admitting a fresh stopper past the teeth 38 and in position to engage the lower teeth 37. When the plunger B ascends, the slide 44 moves upwardly, being actuated by the spring 46; and in this action the arms 39 of the members 34 are lifted, thus permitting the stopper which is held between the members 34 to drop.

The lower terminus of the chute F' comprises a curved chute section 48 carried by a bridge-piece 49 mounted on the member 6 of the bottle-supporting device. The channel 50 of the chute section 48 is inter-

cepted by an inclined perforation 51 through which the stoppering tool works. It will be understood from Fig. 3 that when a stopper descends to the lower portion of the channel 50, it will be maintained in position to be inserted in the bottle-mouth by the stoppering tool.

The pawl-actuating plunger 24, as has been indicated, works on the down stroke to rotate the hopper 26 and the magnet-carrying disk 31. To accomplish this purpose in the best manner, the plunger 24 is equipped with a sleeve 52 which carries a pivot 53 to which is joined a connecting rod 54, whose lower end is connected, by a pivot 55 (see Fig. 3), to the upper end of the stoppering tool plunger B. One lateral wall of the guide E' is provided with a slot 56 which permits movement of the wrist-pin or stud 55. Above the sleeve 52 a collar 57 is secured on the rod 24; and below the sleeve 52 a coil spring 58 encircles the rod 24, the lower end of said spring resting upon a collar 59 which is secured to the rod 24. When the plunger B descends, the connecting rod 54 draws the sleeve 52 down against the force of the spring 58; and the spring 58 acting on the rod 24 serves to actuate the shaft 27 with less suddenness of motion than would occur were the spring 58 omitted.

The improved machine may be adapted to the purpose of applying or inserting seals or stoppers of any desired form. In the illustration given, the operative end of the stopper-applying plunger B is equipped with a composite tool 60 which is adapted to insert artificial stoppers or seals 61. A stopper of this form comprises a cap disk which carries a sealing disk and is surrounded by a locking ring or retainer ring which is adapted to engage an internal locking shoulder in a bottle-mouth. It is unnecessary to describe the stopper-inserting tool in detail.

From the description given it will be understood that when an operator inserts a bottle in the neck-clamping jaws 8 and depresses the foot treadle 3, the lever E will be swung downwardly about the pivot 20, thereby forcing the locking plunger 16 to close the jaws 8. In the same movement, the inclined plunger B will be forced downwardly, thereby causing the tool 60 to effect the insertion of the stopper which rests at the lower end of the channel 50 of the stopper chute. When the plunger B descends, the finger 45 carried by the upper end thereof forces the slide 44 downwardly, thereby causing the fingers 40 to swing downwardly, so that the escapement members 34 will turn on their pivots to withdraw the upper teeth 38 and admit a fresh stopper between the pawls. When the plunger B ascends, the escapement members 34 will be permitted to turn to the position shown in Fig. 5, thereby

permitting the fresh stopper to drop to the lower end of the channel 50, where it rests in position to be forced into a bottle-mouth at the next operation.

In the operation of the improved machine, the spring 1 serves only to elevate the connecting rod D and the stoppering plunger B, so that the spring may be a comparatively light one, thus rendering the work of depressing the foot-treadle lighter than it would be were a heavier spring to be employed. This follows from the fact that it devolves upon the stopper-applying plunger B merely to actuate the operating devices F' through an idle movement to engage the pawl 29 with a fresh tooth of the ratchet wheel 28.

The foregoing detailed description has been given for clearness of understanding only, and no undue limitation should be understood therefrom.

What I regard as new, and desire to secure by Letters Patent is,—

1. In a seal-applying machine, the combination of a standard equipped with an inclined guide, a seal-applying tool reciprocable in said guide, a bottle-support, a lever pivotally supported at its rear end portion on said standard and serving to actuate said tool, a foot-treadle, a connecting rod joining the foot-treadle to an intermediate portion of said lever, a spring in said standard adapted to elevate the connecting rod, seal-selecting and delivering means, including a rotary member, and connecting devices serving to impart motion to said rotary member when the connecting rod is depressed.

2. In a seal-applying machine, the combination of a standard equipped with an inclined guide, a seal-applying tool reciprocable in said guide, a bottle-supporting device, a lever having its rear end portion pivotally supported on said standard and its front end adapted to actuate the seal-applying tool, a connecting rod joined to an intermediate portion of said lever, means for actuating said connecting rod, seal-selecting and delivering means, including a rotary member, and connecting devices serving to impart motion to said rotary member when said connecting rod is depressed.

3. In a seal-applying machine, the combination of a bottle-supporting device, an inclined seal-applying plunger, a lever serving to actuate said plunger, a connecting rod serving to actuate said lever, seal-selecting and delivering means, including a rotary member, and means for actuating said rotary member, including a connecting rod joined to and actuated by said seal-applying plunger.

4. In a seal-applying machine, the combination of a standard equipped with an inclined guide, a reciprocable seal-applying tool in said guide, means for supporting a

- 5 bottle in the path of said tool, a seal-chute having a curved lower terminus with a channel intercepted by an opening for the passage of the seal-applying tool, an escapement device connected with said chute, a slide extending parallel with and actuated by the seal-applying plunger and serving to actuate said escapement, and means for actuating said seal-applying plunger.
- 10 5. In a seal-applying machine, the combination of a standard equipped with an inclined guide, a reciprocable seal-applying tool in said guide, means for supporting a bottle with its mouth in alignment with said tool, a vertically disposed seal chute having a rearwardly curved lower terminus provided with a transverse passage for the seal-applying tool, an escapement device connected with said seal chute above its terminus, from which the seals may drop by gravity to the path of the tool, and means for actuating the seal-applying plunger and the escapement device.
- 15 6. In a machine of the character set forth, the combination of a standard equipped with an inclined guide and below said guide with a pair of inclined neck-clamping jaws, a seal-applying plunger movable in said guide, means for delivering seals to the path of the seal-applying plunger, a jaw-locking plunger disposed beneath said inclined guide, a lever pivotally supported at its rear end and engaging the seal-applying plunger at its front end, the intermediate portion of said lever serving to actuate the jaw-locking plunger, a connecting rod joined to the intermediate portion of said lever, and means for actuating said connecting rod.
- 20 7. In a machine of the character set forth, the combination of a seal-applying plunger, a bottle-supporting device, a chute for feeding seals to the path of said plunger, means for reciprocating said plunger, an escapement device connected to said chute, a slide extending parallel with said plunger and serving to actuate said escapement device, and a finger carried by said plunger and adapted to actuate said slide.
- 25 8. In a machine of the character set forth, the combination of a seal-applying plunger, a bottle-supporting device, a chute for feeding seals to the path of said plunger, means for reciprocating said plunger, an escapement device connected to said chute, a slide extending parallel with said plunger and serving to actuate said escapement device, and a spring finger carried by the upper portion of said plunger and adapted to depress said slide.
- 30 9. In a machine of the character set forth, the combination of a standard equipped with an inclined guide, a seal-applying plunger movable in said guide, a bottle-supporting device, means for delivering seals to the path of said plunger, including a rotary seal-selecting device, means for reciprocating said plunger, a ratchet device adapted to actuate said rotary seal-selecting device, a plunger connected with said ratchet device, a connecting rod joined to the upper portion of said seal-applying plunger and actuated thereby, and spring connections between said connecting rod and said second named plunger.
- 35 10. In a machine of the character set forth, the combination of a standard equipped with an inclined seal-applying plunger, a bottle-supporting device, means for delivering seals to the path of said plunger, including a rotary seal-selecting device, a lever pivotally supported at its rear end on said standard and engaging at its free end said seal-applying plunger, a ratchet device adapted to rotate said seal-selecting device and having a plunger connected therewith equipped with a coil spring, a sleeve on said last named plunger above said spring, a connecting rod joining said sleeve to the seal applying plunger, a foot treadle, a connecting rod joining said foot treadle to an intermediate portion of said lever, and a spring in said standard adapted to elevate said last named connecting rod.
- 40 11. In a machine of the character set forth, the combination of a standard equipped with an inclined guide, a seal-applying plunger movable in said guide, a bottle-supporting device, including a pair of neck-clamping members disposed in an inclined plane, means for delivering seals to the path of said plunger, a locking plunger disposed beneath the seal-applying plunger, a bent lever having a pivotally supported rear end and having its front end engaging said seal-applying tool and its elbow portion engaging said locking plunger, a connecting rod having its upper end joined to the elbow portion of said lever, and means for actuating said connecting rod.
- 45 12. In a machine of the character set forth, the combination of a standard equipped with an inclined guide, a seal-applying plunger movable in said guide, means for actuating said plunger, a bottle-supporting device, a substantially vertical seal chute having a rearwardly curved lower terminus provided with a transverse passage for the seal-applying tool, an escapement device connected with said chute above its terminus, a spring serving to actuate said escapement in one direction, a slide located adjacent to the seal-applying plunger and adapted to actuate said escapement device in the opposite direction, a finger carried by the seal-applying plunger adapted to depress said slide, and means for actuating the seal-applying plunger.
- 50 13. In a machine of the character set forth, the combination with seal-applying

means, of a neck-clamping device comprising a pair of main jaws, a pair of auxiliary jaws mounted thereon and adapted to receive and engage a bottle-neck, and means for moving the main jaws to cause the auxiliary jaws to securely clamp the bottle-neck.

14. In a machine of the character set forth, the combination with seal-applying means, of a neck-clamping device comprising a pair of main jaws, a pair of auxiliary jaws mounted thereon and adapted to receive and engage a bottle-neck, means for yieldingly holding the auxiliary jaws in open position, and means for moving the main jaws to cause the auxiliary jaws to clamp the bottle-neck.

15. In a machine of the character set forth, the combination with seal-applying means, of a neck-clamping device comprising a pair of main jaws, a pair of auxiliary jaws mounted thereon and adapted to receive and engage a bottle-neck, springs adapted to maintain the auxiliary jaws in either open or closed position, and means for actuating the main jaws.

16. In a machine of the character set

forth, the combination with seal-applying means, of a neck-clamping device comprising a pair of main jaws provided with recesses, a pair of auxiliary jaws having shanks received in said recesses and pivotally joined to the main jaws and having also bottle-neck engaging segments, springs adapted to maintain the auxiliary jaws yieldingly in open position, and means for closing the main jaws and maintaining them in closed position during the operation of applying the seal to the bottle.

17. In a machine of the character set forth, the combination of a pair of pivotally mounted main jaws, a pair of auxiliary jaws pivotally mounted on the main jaws and equipped with segments adapted to receive and engage a bottle-neck, a seal-applying plunger, and a jaw-locking plunger adapted to close the main jaws and maintain the same in closed position during the operation of applying a seal to the bottle.
